UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

SELF-BALANCED TURNTABLE.

Application filed May 14, 1923. Serial No. 638,895.

To all whom it may concern:

Be it known that I, FRANKLIN E. ARNDT, a citizen of the United States, residing at Galion, in the county of Crawford and State 5 of Ohio, have invented certain new and useful Improvements in Self-Balanced Turntables, of which the following is a specification.

This invention relates to turntables, and 10 particularly to those turntables which are used in the construction of roads and which are brought up to the point where work is being done upon the road so as to permit the trucks carrying material for the road or for 15 concrete mixers to be turned around so that they may deliver their load and be faced in a reverse direction.

The general object of this invention is to provide a turntable of this character so constructed that as the truck rolls up the approaches or ramps at one end of the turntable the truck will approach and strike the platform, the platform of the turntable being so constructed that the end of the platform 25 adjacent the approach will be depressed to permit the truck to run upon the turntable or platform and balance over the central shaft thereof.

A further object is to provide a turntable 30 of this character in which the platform is balanced upon the central shaft and in which springs are used for the purpose of supporting the platform in its horizontal position, these springs acting as balancing springs and 35 helping to steady the load when being turned and also to hold the platform or table in a horizontal position when the turntable is idle.

A still further object is to provide a turntable 40 of this character having ball bearings, the balls being retained in place by an inverted U-shaped retainer which prevents dirt from dropping in or on the ball race.

Other objects have to do with the details 45 of construction and arrangement of parts as will appear more fully hereinafter.

My invention is illustrated in the accompanying drawings, wherein:—

Figure 1 is a top plan view of my improved 50 turntable;

Figure 2 is a section on the line 2—2 of Figure 1;

Figure 3 is a fragmentary longitudinal elevation;

Figure 4 is a top plan view of the bed;

Figure 5 is a fragmentary section through the bed and through the platform to show the manner in which the springs are mounted.

Referring to these drawings, it will be seen that my construction embodies a supporting base 10 rectangular in plan and consisting of three layers of planks disposed alternately at right angles to each other, held in place by any suitable means, and shod at their forward ends by the upwardly and forwardly inclined steel protectors 11, to which shackles 12 are connected, these shackles in turn being connected to a draft chain or chains 13 whereby this base or wooden platform may be dragged from one place to another.

Mounted upon the platform is the annular track 14. This track is flanged on its inside face and is bolted to the wooden base by bolts 15, the heads of which are countersunk in the bottom of the base. The upper end of the annular rail 14 is grooved, as at 16, to form a ball race for the balls 17. Disposed over this annular track is an annular member 18 which is also cut away to form a race within which the balls 17 operate, this annular member having the lateral flanges 19 extending downward on each side of the head of the rail 14. This member 18, therefore, constitutes an inverted U-shaped retainer rail holding the anti-friction balls 17 in place and protecting the raceways from the accumulation of dirt or other foreign matter. To the lower edge of the inner flange is attached a plurality of stop blocks 20 which are bolted at intervals to the flange and project inward beneath the head of the rail 14 so as to prevent any separation of the annular member 18 from the track.

The annular member 18 is formed at a plurality of points with outwardly projecting 95 bosses 21, and attached to these bosses by set screws 22 are channel iron frame beams 23. The longitudinal members of this rectangular frame 20 extend beyond the transverse members of the frame, and attached to these 100 members are the angularly disposed supporting plates or brackets 24.

Mounted in bearings upon the annular member 18 is a transversely extending shaft 25. This shaft carries upon it a truck platform comprising the relatively wide tracks 26 of relatively thin metal plates. These plates are bolted to the horizontal flanges of longitudinal extending angle irons 27. These angle irons are connected at intervals 110

by transverse angle iron braces 28 which are riveted to the angle irons 27 and to the sheet metal track plates 26. The ends of the track plates are reinforced by means of transverse reinforcing bars 29. There are two of the transverse braces 28 disposed between the ends of the track plates and the annular member 18 and connecting these angle iron braces in the space between the track plates are the 10 crossed braces 30.

Supported upon the brackets 24 are coiled compression springs 31 which at their upper ends bear against plates 32 attached to the under faces of the track plates 26 and held 15 in position by the transversely extending braces 28. Inasmuch as there are four of these springs, it will be seen that the platform of the turntable will be balanced evenly in all directions. In other words, the 20 springs will yieldingly resist any tendency of the turntable to tip from one side to the other on a longitudinal axis and that they will also act to restrain the turntable from tipping on an axis coincident with the trans- 25 verse shaft 25. Riveted to the angle irons 27 are the side pieces 33 which form the side walls of the longitudinally extending tracks. Toward the ends of the tracks the side walls are relatively low, as at 34, and riveted to 30 these relatively low side walls 34 are the socket members 35 which are formed with sockets 36 for the reception of bars 37 whereby the turntable may be manually turned upon its axis.

35 Coacting with the turntable and disposed at one or both ends are the ramps or approaches, designated generally 38. These have floors 39 formed of transversely extending planks, these floors being upwardly 40 inclined and being supported by the lateral walls of these ramps or approaches. The highest part of the ramp is somewhat below the normal level of the platform plates 26 and the ramp is held in place by stakes 45 40 which are driven through angular brackets 41 mounted upon the side walls of the ramps. It will thus be seen that as a truck approaches the turntable it will be driven up the inclined ramp and the wheels of the truck will strike the forward ends of the platform 26 and depress the platform so that the wheels of the truck may run off onto the turntable. This depression of the 50 end of the platform will be resisted by the springs. The truck will then move onto the platform and when the truck is disposed equally over the shaft 25 the weight on the platform will be equalized and the springs will return the platform to its horizontal 55 position. These springs are of such strength that when the truck is in its balanced position disposed equally over the center of the platform, the four springs will support the truck and platform without depression. It 60 65 is only when the truck is running upon the

platform that it depresses one end thereof and rocks the platform upon the axis formed by the shaft 25. Thus these springs act as balancing springs and help steady the load when the turntable is being turned and also hold the turntable in a horizontal position when the table is idle.

After the truck has been disposed upon the turntable the turntable is rotated by power applied to the bars 37 and the truck 75 is turned around end for end so that it may be dumped toward the cement mixer or toward the end of the road upon which work is being done. This disposes, of course, the forward end of the truck in a direction away 80 from the work and permits the truck to run off the platform and proceed on its way without the necessity of backing or turning. This is particularly necessary in narrow roads where there is not sufficient width to 85 permit the truck to readily turn.

It will be seen that without the use of these springs the platform would not balance and would drag at one or the other of its ends, and if the platform was rigid, that is it was not a tilttable platform, it would be necessary to build the ramps up high enough to permit the trucks to run upon the platform and this would mean either that the inclination of the ramps would have to 90 be particularly steep or else that the ramps would have to be relatively long. By pivoting the platform, however, so that it may tilt downward, there is no necessity of this additional length. It will be noted that the 100 platform when it lowers moves down onto the approaches or ramps and is supported thereby but as soon as the truck passes onto the turntable the platform is raised from its engagement with the ramps. By making the 105 platform relatively high, an advantage is gained of having the truck elevated to a height sufficient to clear the curbs of streets and roads and particularly streets or roads which are narrow and have their curb set 110 before the material is hauled in.

It will be seen that the turntable structure which I have devised embodies a base, a circular rail mounted upon the base and constituting a circular raceway, a bed including 115 a frame having a circular raceway confronting the first named raceway, a platform which is tiltably mounted upon the bed, and means yieldingly supporting the platform in a horizontal position but permitting the 120 platform to be tilted downward at one or the other ends so that one end of the platform may be depressed onto the corresponding ramp when a load is unequally distributed upon the platform but that when 125 the load is evenly distributed upon the platform the springs will return the platform to its horizontal position. It is not intended that the springs shall be depressed under a load but merely that the springs shall auto- 130

matically return the platform to its horizontal position when the truck has passed the tilting center of the platform and is equally disposed on each side of said center.

5 It will, of course, be seen also that the springs tend to prevent any lateral tilting of the platform which would place strain upon the shaft.

I claim:—

10 1. In a turntable, a base, an annular track supported upon the base, a bed piece rotatably mounted upon the track, a platform tiltably mounted upon the bed piece but rotatable therewith, and springs carried by 15 the bed piece and yieldingly holding the platform in a horizontal position.

2. A turntable including a base, an annular track operatively supported upon the base, a bed piece coacting with the track, 20 there being anti-friction bearings between the track and the bed piece, a platform tiltably mounted upon the bed piece, and a pair of springs mounted upon the bed piece and disposed on each side of the tilting axis of 25 the platform and normally supporting the platform in a horizontal position but permitting the tilting of the platform under an unevenly disposed load.

3. A turntable comprising a base, a frame 30 mounted upon the base and including a circular track, a bed mounted upon said track for rotation thereon, a transversely extending shaft mounted in bearings on the bed and extending across the center thereof, a platform 35 operatively connected to said shaft to tilt therewith, and springs supported upon the bed and operatively engaging the platform, the springs being disposed on each side of the axial center of said shaft to normally support the platform in a horizontal 40 position to permit the tilting of the platform under an unevenly distributed weight.

4. A turntable comprising a base, a frame 45 mounted upon the base and including a circular track, a bed comprising a frame including a circular rail confronting the circular track, anti-friction bearings between the rail and track permitting the rotation of the rails with relation to the track, a 50 rock shaft mounted in bearings on the bed, a platform carried by said shaft and tilting therewith, springs mounted upon the bed and engaging the platform and yieldingly supporting the platform in a horizontal 55 position but permitting the platform to be tilted under an unevenly disposed load, and manually operable means attached to the platform whereby it may be rotated.

5. A turntable comprising a base, a bed 60 rotatably mounted upon the base and a platform mounted upon the bed for oscillation in a vertical plane, means yieldingly supporting the platform in a horizontal position but permitting the platform to be tilted under 65 an unevenly distributed load, upwardly in-

clined ramps disposed below the ends of the platform and having their upper ends on a level below the level of the platform, the platform being depressible at each end into engagement with said ramps, and means 70 whereby the platform and bed may be rotated.

6. A turntable comprising a base, a frame mounted upon the base and embodying a circular track, a bed mounted upon the base 75 and also embodying a circular track confronting the first named track, the second named circular track being U-shaped in cross section to provide flanges embracing the first named track, anti-friction bearings 80 disposed between the two tracks, a shaft mounted upon said bed, a platform operatively mounted upon the shaft, the platform being oscillatable in a vertical plane around the axis of said shaft, and springs yieldingly urging said platform to a horizontal position but permitting the tilting of the platform under an unevenly distributed load.

7. A turntable of the character described comprising a base including an annular track, 85 a bed including an annular track coacting with the first named track, anti-friction bearings disposed between the two tracks whereby the bed may rotate upon the base, a platform oscillatably mounted upon said bed, coiled 90 compression springs disposed in lines radial to the rotative center of the turntable and operatively supporting said platform against depression but permitting the platform to be depressed at one end or the other 100 under the action of an unevenly distributed load.

8. A turntable of the character described comprising a base, a bed mounted upon the base and including a rectangular frame and 105 a circular track, a bed mounted upon said base and including a rectangular frame coacting with the first named track, there being anti-friction bearings between the two tracks, a platform including a rectangular 110 frame, a shaft operatively supporting the platform from the bed and permitting oscillation of the platform in a vertical plane, and springs disposed at the corners of said frames and yieldingly supporting said platform in a horizontal plane but permitting the depression of the platform at either end under the action of an unevenly distributed load.

9. A turntable of the character described 120 comprising a base, a bed mounted upon the base and including a rectangular frame, the bed and base having confronting circular raceways and anti-friction elements disposed between the confronting faces of the raceways, a transverse shaft mounted upon the bed and extending diametrically across and above the circular raceways, a platform mounted upon the shaft and embodying a rectangular frame and two parallel rela- 125 130

tively wide troughs U-shaped in cross section extending longitudinally of the turntable and at each end beyond said frame, the longitudinal members of said shafts being connected by transverse braces, and springs disposed upon said bed and engaging the corners of the frame and supporting the frame and platform in a horizontal position but permitting the platform to tilt in a vertical

plane around the axis of said shaft, and upwardly inclined ramps having their higher ends disposed beneath the platform and the floor at the upper ends of said ramps being below the platform, the platform being depressible onto said ramps. 10

15 In testimony whereof I affix my signature.

FRANKLIN E. ARNDT.
